UNITED STATES PATENT OFFICE.

PHILO P. STEWART, OF TROY, NEW YORK.

IMPROVEMENT IN STOVES.

Specification forming part of Letters Patent No. **38,361**, dated April 28, 1863.

To all whom it may concern:

Be it known that I, PHILO P. STEWART, of the city of Troy, county of Rensselaer, and State of New York, have invented new and useful Improvements in Coal-Stoves; and I do hereby declare that the following is a full and exact description of the construction and operation of the same, reference being hereby had to the accompanying drawings, making a part of this specification.

Like letters represent and refer to like or corresponding parts.

Figure 1 is a vertical section through the center from the front door to the exit-pipe, showing the improvements herein described and set forth. Fig. 2 is a transverse section through the fire-chamber and oval cylinder, hereinafter described and set forth. Fig. 3 is the front door opening into the fire-chamber, and hereinafter described.

The nature of my invention consists in constructing the cylinder of the fire-chamber with an annular hot-air chamber between the fire-brick forming the inside of the said fire-chamber and the said cylinder which forms the outside part of the said fire-chamber cylinder, which said annular hot-air chamber communicates with the said fire-chamber by means of apertures through the said fire-brick, so as to admit therein hot air from said annular chamber, as hereinafter described.

It also consists in the arrangement of a cold-air chamber over the fire-chamber, in connection with a cold-air chamber in the front door opposite thereto, so as to cause the gases or other combustible material arising from said chamber below to ignite by means thereof.

To enable others skilled in the art to which my invention relates to construct and use the same, I will here proceed to describe the construction and operation thereof, which is as follows, to wit:

I construct the outside cylinder *c*, Figs. 1 and 2, of cast-iron of any diameter, height, or thickness required. On the inside of this cylinder I cast projections *i*, Figs. 1 and 2, which are of any required number to answer the purpose desired, and upon any part of the said cylinder deemed best, and are for the purpose of supporting the fire-brick *d*, and at the same time form the annular chamber *s*, Figs. 1 and 2, which chamber is for the circulation of air admitted thereto from the lower part

thereof, which opens directly into the ash-pan and air-chamber *g*, Fig. 1, and which said chamber *s* extends the whole height of the fire-chamber, and which heats the air entering therein, as aforesaid, preparatory to its introduction, in a highly heated condition, into the fire in the fire-chamber through the apertures *r* in the said fire-brick *d*, Figs. 1 and 2. The said annular hot air chamber *s* will in size depend upon the length of the projections *i*. Each tier of fire-brick *d* is supported by these projections at or near the top and bottom thereof, while between the same may be seen the apertures *r* at the joints of the said brick, Fig. 1. Highly-heated air is continually entering the said fire-chamber at different points around the same through the said apertures *i*. Over and above the said fire-chamber and said hot-air-chamber *s*, I construct the projecting cold-air-chamber *k*, which has a thick cast-iron plate, *m*, projecting into the chamber *t* upon any angle desired, through which are apertures *n*, which communicate from the cold-air chamber *k* to the chamber below. The cold air enters the said chamber *k* through the tube *l*, which opens into the room where the stove is used. The upper plate, which forms said chamber *k*, may be in any form desired, and is securely fastened to the plate below. This chamber may extend over as much space as may be found necessary. The outside wall of this chamber extends from one side of the door *w* around the top of the fire-chamber below and until it reaches the opposite side of the said door, and is seen at *x*, Fig. 1. Between the said plate *m* and the said door *w* there is an open space for the waste product of combustion to pass into the draft communicating with the exit-pipe *j*. The front door, *w*, is constructed with a cold-air chamber, *z*. This chamber is formed by means of mica, *o*, Figs. 1 and 3, and wire-gauze or perforated plate *p*, Fig. 1. The mica *o* has small apertures *u*, Fig. 3, through which cold air enters into the chamber *z*, thence through the wire-gauze *p*, and, coming in contact with the air which enters the fire-chamber through the perforated plate *m* from the chamber *k*, and also with the heat arising from the fire-chamber below, causes the gases and smoke arising therewith to ignite and burn, which, in connection with the gas-burning arrangement around the outside of the fire-

chamber, makes a very perfect gas and smoke consumer. The said door *w* is in the outer cylinder *a* and directly opposite the said air-chamber *k*.

a a, Figs. 1 and 2, is the outer cylinder, and may be of any size or shape. This cylinder forms the flues *h h*, Fig. 2, which are for the purpose of receiving heat from the fire-chamber, and a downward draft, produced by closing the damper *y* in the funnel *A*, which connects the chamber *t* to the tube or exit-pipe *j*. With said damper closed the draft will be from the chamber or ash-pit *g* up through the fire-chamber, in part against the plate *m*, along the surface of the same, and between the upper end of the same and the door *w*, over the top of the chamber *k*, thence down the said flues *h h*, Fig. 2. When at the bottom thereof, the currents unite and pass up the tube or exit pipe *j*. When this damper *y* is open, then a direct draft is had, in which case a stronger fire is created. The air to supply combustion is admitted to the lower part of the said fire-chamber in the usual manner. The coal in the fire-chamber rests upon any fire-grate which will answer the purpose, and which grate is operated in any way

or manner deemed best. *b b*, Figs. 1 and 2, is an inside cylinder, and is for the protection of the said outer cylinder *a* from undue heat from the fire-chamber within the said cylinder, which is made of sheet-iron.

Having thus described my improvements in coal-stoves, what I claim, and desire to secure by Letters Patent of the United States, is—

1. The combination of the outer fire-cylinder *c* with the annular hot-air chamber *s*, and with fire-brick perforated and forming the inner fire-cylinder *d*, in the manner substantially as herein described and set forth.

2. The perforated plate *m* and cold-air chamber *k*, in combination with the door *w*, having therein the cold-air chamber *z*, the whole being arranged over the fire-chamber and annular hot air chamber *s*, substantially as and for the purposes herein described and set forth.

In testimony whereof I have, on this 19th day of August, 1862, hereunto set my hand.

PHILO P. STEWART.
